US00D834594S

(12) **United States Design Patent** (10) Patent No.: **US D834,594 S**
Anzures et al. (45) Date of Patent: **** Nov. 27, 2018**

**(54) DISPLAY SCREEN OR PORTION THEREOF
WITH GRAPHICAL USER INTERFACE**

CPC G06F 3/048-3/04897
See application file for complete search history.

(71) Applicant: **Apple Inc.**, Cupertino, CA (US)

(57) **CLAIM**

The ornamental design for a display screen or portion thereof with graphical user interface, as shown and described.

DESCRIPTION

The FIGURE is a front view of a display screen or portion thereof with graphical user interface showing the claimed design.

The outermost broken lines in the FIGURE show a display screen or portion thereof, and form no part of the claimed design. The other broken lines in the FIGURE show portions of the graphical user interface that form no part of the claimed design.

1 Claim, 1 Drawing Sheet
